UNITED STATES PATENT OFFICE.

LOUIS KUHN, OF MILWAUKEE, WISCONSIN, ASSIGNOR TO AMERICAN CANDY CO., OF MILWAUKEE, WISCONSIN, A CORPORATION OF ILLINOIS.

DESIGN FOR A PAPER CARTON.

Application filed February 20, 1922. Serial No. 792. Term of patent 7 years.

To all whom it may concern:

Be it known that I, LOUIS KUHN, a citizen of the United States, residing at Milwaukee, in the county of Milwaukee and State of Wisconsin, have invented a new, original, and ornamental Design for Paper Cartons, of which the following is a specification, reference being had to the accompanying drawing, forming part thereof.

The figure is a perspective view showing my new and ornamental design.

I claim:

The ornamental design for a paper carton, as shown.

In testimony that I claim the foregoing I have hereunto set my hand at Milwaukee, in the county of Milwaukee and State of Wisconsin.

LOUIS KUHN.
